ABSTRACT OF THE DISCLOSURE

A paperboard container which maintains a sterile condition about an article is weakened by a pair of container girding parallel lines of scoring which, respectively, penetrate the container wall from inside and outside surfaces. Thereby, the container can be pulled apart to enable article removal through a container opening defined by an inner surface which has been protected from contamination by an overlapped container portion.

The present invention relates to aseptic packages. Particularly the invention relates to a package from which a sterile article can be removed without being sullied by surface contaminants.

A conventional package for aseptic articles such as surgical implements or instruments and their trays comprises a paperboard sleeve, for imparting package rigidity to facilitate handling and storage, and a polyethylene overwrap for facilitating content sterilization and retaining content sterility. Normal handling of a conventional package may result in content contamination due to abrasive or other rupture of its polyethylene overwrap, some of which may go undetected and cause associated disastrous consequences. However, the gas perviousness, of polyethylene, by reason of which package contents are readily sterilized, and bacterial imperviousness lend desirable characteristics to a conventional package which far outweigh its potential hazard.

Sterile packages in which paperboard is employed as the only enclosure for an article overcome or eliminate the hazard attendant the use of polyethylene. Furthermore, paperboard is bacteria impervious and has desirable breathing characteristics for permitting gas interchange. Moreover, paperboard imparts toughness and rigidity to a container to facilitate its handling and storage. However, heretofore, save for an overwrap which can be pulled back over the dispensing end of a paperboard sleeve, no expedient has been known which eliminates the high risk of contamination about the edges of an opening generated in a paperboard container for removal of aseptic contents.

It is an object of the present invention to provide an improved aseptic package.

It is another object of the invention to provide an improved sterile package comprised of a paperboard container.

It is an additional object of the invention to provide an improved unitary overwrapping structure for an aseptic article.

It is a further object of the invention to aseptically remove a sterilized article from a container.

It is a yet further object of the invention to permit withdrawal in an aseptic condition of a sterilized article through an opening torn in a rigid package.

The features in a package by which the foregoing objects are achieved include a container for maintaining a therein disposed article in a sterile condition. The container comprises a pair of sections having an integrated continuous condition in which the sections are arranged in overlapping relationship for aseptically enclosing the

2

article and a discrete condition in which the sections are disconnected each from the other to provide an opening for article removal in one of said sections.

The foregoing and other objects, features and advantages of the invention will become more apparent upon consideration of the following description and appended claims, when considered in conjunction with the accompanying drawings wherein the same reference character or numeral refers to like or corresponding parts throughout the several views.

FIG. 1 is a side elevational view of a package embodying the present invention parts being broken away for the purpose of illustration.

FIG. 2 is a perspective view of said package showing a pair of container sections discretely conditioned and disconnected each from the other.

FIG. 3 is a section according to the broken section line 3—3 of FIG. 2.

Referring now more particularly to the drawings, a package 10 which embodies the invention comprises a container 11 and a therein disposed article 12. Herein, the latter is shown as a surgical tray which it is desirable to store in an aseptic condition until it is ready for use. Container 11 may be of rigid paperboard fabrication and formed from a sleeve whose opposite ends 14 and 15 are gable fashioned and aseptically sealed about article 12. Container 11 (once formed) is characterized by a wall 16 with an outer surface 17 and an inner surface 18 enclosing article 12. The character of the paperboard of the container is such that it is pervious to package distending gases following sterilization according to conventional techniques and impervious to bacteria by reason of which article 12 once sealed within package 10 and sterilized will retain its aseptic condition until package 10 has been broken.

Inasmuch as it is desirable to dispense article 12 aseptically, container 11, in accordance with the teachings of the present invention, comprises a pair of opposite gabled end sections 19 and 20. Said sections have an integrated continuous condition in which they are arranged in overlapping relationship for aseptically enclosing article 12 as illustrated in FIG. 1. However, each of end sections 19 and 20 has a second or discrete condition in which it is completely disconnected from the other section to provide in one of the sections (herein section 19) an opening 21 for removal of article 12. The portions of wall 16 comprising end sections 19 and 20 and accordingly each of end sections 19 and 20 is defined by a corresponding part of outer surface 17 and inner surface 18. As illustrated in FIGS. 2 and 3 outer surface 17 has been removed from about opening 21 when end sections 19 and 20 are discretely conditioned, that is, when they are disconnected each from the other. The latter arrangement or conditioning prevents article 12 from coming in contact with outer surface 17 as it is removed from opening 21 and thereby prevents said article from becoming sullied by outer surface contamination. The desired condition is achieved because outer surface 17 of end section 20 adjoining section 19 is underlain by inner surface 18 defining opening 21 when said end sections are arranged in integrated continuous condition.

Wall 16 is characterized by an area of weakness 24 (FIG. 1) for disconnecting end sections 19 and 20. Said area of weakness in the integrated condition of the container comprises an outer layer 22 which is co-extensive with outer surface 17 and defines an opening 27 in end section 20 when the latter is in its discrete condition. Outer layer 23 when in its integrated condition is superposed and integral with respect to an inner layer 23 which is co-extensive with inner surface 18 and which when discretely conditioned defines opening 21. By reason of area

of weakness 24 end sections 19 and 20 may be merely pulled apart to generate openings 21 and 27. Area of weakness 24 is defined by a pair of parallel lines of scoring 25 and 26 which gird container 11 as shown in FIG. 1. Line of scoring 25 projects from inner surface 18 partially into wall 16; whereas, line 26 projects from outer surface 17 partially into wall 16. As a consequence of the foregoing arrangement, when a pulling force is exerted at opposite ends 14 and 15 of the container, the outer layer 22 will move with the container end section 20 while the inner layer 23 will remain with section 19.

Preferably lines of scoring 25 and 26 are offset toward end 14 so that section 20 in effect becomes a cap for container section 19. The latter section being a larger section will retain the article 12 when the sections are separated. Through the exercise of a little care, and because the part of outer surface 17 about opening 21 is removed from about article 12 when the container sections are pulled apart, article 12, can be easily dispensed through opening 21 in an unsullied condition because it can be readily prevented from engaging outer surface 17.

As many substitutions and changes could be made in the above described construction, and as many apparently widely different embodiments could be constructed without departing from the scope and spirit thereof, it is intended that all matter contained in the accompanying specification shall be interpreted as being illustrative and not in a limiting sense.

What is claimed is:

1. In a package comprised of a container defined by a

5 tubular construction closed at its opposed ends for maintaining a therein disposed article in a sterile condition, said container having an integrated continuous condition for aseptically enclosing said article and a separated condition forming a pair of disconnected sections to provide in one thereof an opening for article removal, the improvement in said container comprising a continuous wall with perforations extending partially therethrough from opposite sides and defining an area of weakness for disconnecting said sections and forming overlapping layers about said opening.

10 2. A combination according to claim 1 in which said area of weakness comprises a pair of parallel lines of scoring girding said container in different planes.

15 3. A combination according to claim 1 in which said wall has inner and outer surfaces, one of said lines of scoring extending into said wall from said inner surface, the other of said lines of scoring extending into said wall from said outer surface for removing an outer layer containing said outer surface with one of said sections from about a part of an inner layer containing said inner surface of the other of said sections to prevent external surface contamination about said opening.
